DESIGN FOR A LINE GUIDE FOR FISHING RODS

William I. Treadway, Bristol, Conn., assignor to
The Horton Manufacturing Company, Bristol,
Conn., a corporation of Connecticut

Application August 15, 1944, Serial No. 114,890

Term of patent 14 years

(Cl. D31—4)

To all whom it may concern:

Be it known that I, William I. Treadway, a citizen of the United States, residing at Bristol, in the county of Hartford, State of Connecticut, have invented a new, original, and ornamental Design for a Line Guide for Fishing Rods, of which the following is a specification, reference being had to the accompanying drawing, forming a part thereof.

In the accompanying drawing:
Figure 1 is a perspective view of a line guide showing my new design;

Fig. 2 is a top view thereof; and
Fig. 3 is a side view of the same.

I claim:

The ornamental design for a line guide for fishing rods, substantially as shown.

WILLIAM I. TREADWAY.
